UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,079,498.

Specification of Letters Patent.

Patented Nov. 25, 1913.

Application filed June 12, 1912. Serial No. 703,118.

To all whom it may concern:

Be it known that I, DAVID S. KENNEDY, a citizen of the United States, and a resident of Brooklyn, county of Kings, and State of New York, have invented a new and useful Improvement in Typographical Machines, of which the following is a specification.

My invention relates to typographical machines, such as linotype machines of the general organization represented in Letters Patent of the United States, No. 436,532, to O. Mergenthaler, wherein circulating matrices are released from a magazine in the order in which their characters are to appear in print, and then assembled in line together with spacers, the composed line transferred to the face of a mold, the mold filled with molten metal to form a slug or linotype against the matrices which produce the type characters thereon, and the matrices thereafter elevated and returned through a distributing mechanism to the magazine from which they started.

More specifically, it has reference to typographical machines, wherein the magazine is interchangeable, so that any desired face or font may be brought into use, as illustrated for instance, in Letters Patent of the United States to T. S. Homans, No. 830,436. In the use of such machines, and particularly when the escapements are connected to or carried by the magazine, it sometimes happens that an attempt to move the latter, without first disconnecting the escapements and their actuating devices, results in the breakage or distortion of these parts. To overcome this objection, I have provided means to lock the magazine against removal, and these means are connected to the parts which engage and disengage the escapements and their actuating devices, in such manner that the magazine may not be moved unless the escapements are properly freed.

In the accompanying drawing, I have shown my invention in preferred form and by way of example, and in connection with a specific type of machine, but obviously many changes and variations may be made therein, and in its mode of application, without departure from its spirit.

Generally speaking, I desire it to be understood that I do not limit myself to any

specific form or embodiment, except in so far as such limitations are specified in the claims.

The drawing is a side view of a portion of a linotype machine, showing a removably mounted magazine and the connected parts, 60 with my invention applied thereto.

The magazine A is supported by the frame A¹, which is pivotally connected as at A² to the machine frame, in such manner that the magazine may be brought into operative relation to the face-plate B, or be raised above it and into position to be drawn forward from the machine without interference with the other parts. This movement of the frame A¹ about its pivot A² is preferably effected by the operation of a pair of cam arms C on the opposite ends of the transverse rock shaft C¹ mounted in the frame A¹, the cam portions of the arms C resting upon and being adapted to co-operate with rollers C² on the main frame.

The parts and operations so far described are or may be substantially like those disclosed in the said Homans patent. In the present instance, however, it will be noted that the escapements D are connected to and carried by the magazine, which arrangement differs from that of the Homans patent. The escapements are actuated in the usual manner by the reeds E, the upper ends of the latter being mounted in a slide F, the lateral movement of which effects the engagement and disengagement of the reeds and escapements. The slide F is operated by the handle G on the rock shaft G², which is mounted in the main frame and which carries at its opposite ends two crank arms G³, connected as at G⁴ to the slide F. These specific connecting and disconnecting means, however, in themselves, constitute no part of my invention, as any similar or equivalent mechanism may be substituted therefor. Also mounted on the rock-shaft G² is the locking arm J, so formed and located as to engage the stud C² on the cam arm C, when the handle is moved to engage the reeds and escapements. When in this position, the cam arm C is locked and held, thus preventing the movement of the frame A¹ and the magazine A supported thereby.

When the handle G is operated to disconnect the reeds from the escapements, the arm J is moved out of engagement with

the stud C², and the cam arm C may then be manipulated to move the magazine frame and magazine, and to permit the removal and replacement of the latter in the ordinary manner.

It will be seen that the operative connection of the reeds and escapements effects the locking of the magazine elevating cams, thus preventing the movement of the magazine and obviating the liability to damage of these connected parts; and viewing it from the opposite standpoint, the unlocking of the magazine elevating cams disengages these parts, so that the magazine may be freely moved and replaced, if desired.

As above stated, my invention has been shown merely in preferred form and by way of example, and as applied to a particular style of machine, but obviously many changes and variations therein, and in its mode of application, will suggest themselves to those skilled in the art and still be comprised within its scope.

Having thus described my invention, its construction and mode of operation, what I claim and desire to secure by Letters Patent of the United States is as follows:

1. In a typographical machine, the combination of a removable magazine provided with escapements, actuating devices connected to the escapements, and further means to prevent the removal of the magazine until said actuating devices are disconnected from the escapements.

2. In a typographical machine, the combination of a removable magazine provided with escapements, means for moving the magazine from its operative position to permit its removal, actuating devices connected to the escapements, and further mechanism for locking the magazine-moving means against action when the actuating devices are connected to the escapements.

3. In a typographical machine, the combination of a removable magazine provided with escapements, escapement actuating devices, and means for connecting the escapements and their actuating devices and simultaneously locking the magazine against removal.

4. In a typographical machine, the combination of a removable magazine provided with escapements, means for locking the magazine against removal, escapement actuating devices, means for connecting the escapements and their actuating devices, and connections between the magazine locking means and the said connecting means, where-

by the removal of the magazine will be prevented when the escapements are connected to their actuating devices.

5. In a typographical machine, the combination of a removable magazine provided with escapements, means for locking the magazine against removal, actuating devices connected to the escapements, and mechanism for simultaneously effecting the disconnection of said actuating devices and the unlocking of the magazine.

6. In a typographical machine, the combination of the removable magazine A provided with the escapements D, its magazine supporting frame A¹ pivotally mounted upon the main frame, the cam arm C for elevating the frame A¹, the escapement actuating reeds E, the movable frame F for connecting and disconnecting the reeds E and escapements D and the device J connected to the frame F for locking and unlocking the cam arm C.

7. In a typographical machine, the combination of the pivotally mounted magazine frame A¹, the cam arm C carried thereby to elevate the same, the escapement actuating reeds E movable to and from operative position, and the device J to lock the cam arm C and controlled in its action by the movement of the reeds E.

8. In a typographical machine, the combination of the magazine A provided with escapements D, its supporting frame A¹, the cam arm C for elevating the frame, the escapement actuating reeds E, the movable frame F for connecting and disconnecting the reeds E and the escapements D, the handle G for moving the frame F, the rock shaft G² upon which said handle is mounted, and the device J also mounted upon the shaft G² to lock and unlock the cam arm C.

9. In a typographical machine, the combination of the movable frame A¹, the cam arm C, the reeds E, and connected means for shifting the reeds E and locking the cam arm C.

10. In a typographical machine, the combination of the movable magazine frame A¹, the cam arm C, reeds E, operating handle G, locking arm J to engage the cam arm C, and frame F to shift the reeds E.

In testimony whereof I hereunto set my hand this tenth day of June, 1912, in the presence of two attesting witnesses.

DAVID S. KENNEDY.
